UNITED STATES PATENT OFFICE.

JAROSLAUS VOKALEK, OF SAVANNAH, GEORGIA.

DEODORIZING ATTACHMENT FOR FANS.

1,267,826.

Specification of Letters Patent. Patented May 28, 1918.

Application filed November 13, 1916. Serial No. 131,041.

To all whom it may concern:

Be it known that I, JAROSLAUS VOKALEK, a citizen of the United States, residing at Savannah, in the county of Chatham and State of Georgia, have invented certain new and useful Improvements in Deodorizing Attachments for Fans, of which the following is a specification.

The present invention relates to new and useful improvements in atmosphere deodorizing attachments for fans and the like, the device having as an object the provision of a novel and improved type of deodorant container and dispenser for association with an electric fan or the like, whereby the deodorant contained in the device may be mingled with the air currents derived from the fan and caused to permeate the atmosphere of a room either to perfume the same or to kill any possible germs which may be in the atmosphere.

Another object of my invention is to provide a deodorizing attachment of the class referred to which may be readily applied to any electric fan having a standard guard frame without structurally altering the fan or the attachment.

A further object of my invention is to provide a device of the character described which may be adjusted to various sizes of fan guards and which, when applied presents a neat appearance and will require little attention until in need of replenishing.

A still further object of my invention is to provide a device of the character described which feeds automatically, being barometric in action, the deodorant being supplied automatically as the same evaporates in the evaporating tray.

A still further object of my invention is to provide a device of the character described which may be cheaply manufactured and sold, is strong and durable, and may be readily disassembled for cleaning.

Other objects and advantages to be derived from the use of my improved deodorizing attachment for fans will appear from the following detailed description and the claims, taken with an inspection of the accompanying drawings, in which:

Figure 1 is a front elevational view of an electric fan of the standard type showing my improved deodorizing attachment applied thereto;

Fig. 2 is a side elevational view of the deodorizing device; and

Fig. 3 is a vertical sectional view of the same, the container being shown in elevation.

Referring more specifically to the drawings, wherein similar characters of reference designate like and corresponding parts throughout the various views, F designates an electric fan having the usual base B and guard frame G.

The device of my invention includes a deodorant carrying tray 10 having marginal flanges 11 to form a receptacle for a deodorant, the same being exposed to action by the air currents from the fan to evaporate in a room or the like and become mingled with the atmosphere thereof. A connection supply pipe 12 is cast integrally with the tray 10, the lower end 13 of said supply pipe being disposed below the upper marginal edges of the flanges 11 and below the level of the liquid in said tray for a purpose which will hereinafter appear. The tray 10 is supported on the lower portion of the frame G by means of a clamp 14, said clamp being formed with gripping jaws 15 to be engaged with the frame, a tightening screw 16 passing through said jaws to retain the same in engagement with the frame. The jaws are inherently resilient and when the screw is loosened tend to expand. The clamp 14 is hingedly connected with an extension 17 formed on the tray 10 as indicated at 18, the connecting member 18 being in the form of a screw passing through the clamp and said extension 17 so as to angularly adjust the tray relative the clamp. Of course, I do not limit myself to the shape of the clamping jaws as shown.

A main container is provided in the form of a glass jar or the like 20 having a neck 21 extending therefrom. A turning plug valve 22 is interposed in the neck 21 to control the flow of liquid therethrough. It is, of course, to be understood that a liquid deodorant is employed in connection with my invention. The lower free end of the neck 21 is in threaded engagement as at 23 with an outlet nozzle member 24, said connection being insured against leaking by means of a washer 25. A clamp 26 is carried by the nozzle member 24, the lower end of the latter being reduced to receive said clamp. The clamp 26 is provided with grip-

ping jaws 27 maintained in engagement with the upper portion of the frame G by means of a tightening screw 28. A short length of rubber or other flexible tubing 5 29 connects the nozzle member 24 with the short length of pipe 12, different lengths of tubing being employed for various diameters of guard frames.

The operation of my improved deodorizing attachment will be apparent from an inspection of Fig. 1. It will be noted that the air currents set up by the fan pass over the tray 10 evaporating the contents thereof. As long as the level of the deodorizing liquid is 10 maintained above the lower end of the pipe 12 no liquid will flow from the container 20. However, as soon as the liquid level in the tray falls below the lower end of the pipe 12 a new supply will be delivered to the tray. 15 Until the container 20 is exhausted the device needs practically no attention. The invention is adapted to move with the frame in the event that the same be used on an oscillating fan. The liquid supply may be entirely cut off by the valve 22. 20

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed. 25

Having thus fully described my invention,

what I claim as new and desire to secure by Letters Patent, is:—

1. In a deodorizing attachment for fans and the like, the combination of a liquid receiving tray, and barometrically controlled supply means therefor. 40

2. In a deodorizing device for fans and the like, the combination of a liquid deodorizing receiving tray, means to fasten said tray on a fan guard or the like, a container, a supply nozzle associated therewith, means to mount said supply nozzle on said fan guard, and a conduit connecting said nozzle with said receiving tray. 45

3. In a deodorizing device for attachment to fans and the like, the combination of a liquid deodorant receiving tray, an angularly adjustable clamp member carried by 55 said tray to engage a fan guard frame, a liquid container, valve control means associated therewith, an outlet nozzle, means to support said outlet nozzle on said frame, and a conduit connecting said outlet nozzle with 60 said tray, said conduit extending to said tray and opening beneath the liquid level in the tray whereby to barometrically control the supply of liquid thereto. 65

4. In a deodorizing attachment for fans, 65 a liquid receiving tray mounted in proximity to the fan, an inlet pipe formed integral with said tray, a container arranged about the tray, and conveying means communicating with said pipe and said container. 70

In testimony whereof, I affix my signature hereto.

JAROSLAUS VOKALEK.
